TYPEWRITER LIFT MECHANISM

Walter Carl McMahan, Escondido, Calif.

Application February 24, 1951, Serial No. 212,535

4 Claims. (Cl. 312—27)

1

This invention relates to typewriter lift mechanisms especially adapted to be incorporated in desks.

Such lifts commonly employ a shelf that may be manually moved from an inactive position below the desk top to an active position projecting outwardly of the desk, and at a convenient height.

Various means, such as springs, may be used in such mechanisms, and which partly compensate for the weight of the typewriter supported on the shelf, to facilitate the manual lifting and lowering of the shelf.

It is one of the objects of this invention to provide a simplified mechanism of this character, and particularly one in which the manual operation of raising and lowering the typewriter support or shelf is facilitated.

It is another object of this invention to provide a support which, when elevated, is positively restrained against inadvertent lowering or sideways tilting of the shelf.

It is another object of this invention to provide a typewriter support that is rigid and that will not vibrate while the operator uses the typewriter.

This invention possesses many other advantages, and has other objects which may be made more clearly apparent from a consideration of one embodiment of the invention.

For this purpose, there is shown a form in the drawings accompanying and forming part of the present specification. The form will now be described in detail, illustrating the general principles of the invention; but it is to be understood that this detailed description is not to be taken in a limiting sense, since the scope of this invention is best defined by the appended claims.

Referring to the drawings:

Figure 1 is a vertical section of a typewriter desk incorporating the invention, the typewriter support being in lowered position;

Fig. 2 is a fragmentary sectional view, taken along a plane corresponding to line 2—2 of Fig. 1;

Fig. 3 is a view similar to Fig. 1, but illustrating the typewriter support in extended or raised position;

Fig. 4 is an enlarged sectional view, taken along a plane corresponding to line 4—4 of Fig. 3; and

Fig. 5 is an enlarged sectional view, showing the latch-releasing mechanism used in connection with the invention.

A typewriter desk is shown having a top 1, a back wall 2, walls 3, and legs 4.

2

To provide a space 50 for a typewriter at the right-hand side of the desk, a vertical partition 5 (Figs. 2 and 4) extends between a lower desk brace 6 and the top 1.

5 A shelf-like support 7 is adapted to be disposed in the lowered position beneath the top 1, as indicated in Figs. 1 and 2, or to extend forwardly to a position near the top of the desk 1, illustrated in Figs. 3 and 4. In Fig. 3, a typewriter 24 is shown as resting on support 7.

In order to suspend the support 7 in space 50, use is made of four links, two at each edge of the support 7. Thus, links 8 and 9, shown in Fig. 1, are pivoted at their lower ends to one edge 10 of the support 7. At their upper ends these links are pivoted by pivots 22 and 23 on a supporting cleat 10 that is attached to a cleat 11 fastened to the partition 5. A similar supporting cleat 12 (Fig. 2) is attached to a cleat 13 that is placed at the top of the inner side of the wall 3. From this support 13 there extend two links 8 and 9, similarly arranged to the links shown in Fig. 1. In the lowered position of Figs. 1 and 2 the cleats 10 and 12 are in juxtaposed relationship with respect to the support 7. The links 8 and 9 are movable to a substantially coincident relationship with respect to the cleats 10 and 12, thereby by swinging the support 7 out of juxtaposed relationship with respect to the cleats 10 and 12 and the top 1, as illustrated in Fig. 3.

In the lowered position of Fig. 1, the support 7 is held against inadvertent forward movement, as by the aid of a spring catch 14 fastened to the lower side of the support 7, and adapted to engage a detent 15. This detent 15 is supported near the lower edge of the typewriter opening 50. The catch 14 may be released from the detent 15 by manually raising this spring latch by the aid of the horizontal end 16. When the support 7 is lowered, the catch 14 rides over the detent 15 until the parts reach the position of Fig. 1, when the catch snaps into latching position.

A pair of tension springs 17 and 18 is provided 45 for urging the support 7 to the lowered position of Fig. 1 or to the raised position of Fig. 3. When the support 7 is in the lowered position, the springs exert a force urging the links 8 and 9 in a counterclockwise direction, thereby maintaining the support 7 in the lowered position. When the latch 14 is released and the support 7 brought forward to a definite point, the springs 17 and 18 then exert a force assisting the raising operation.

Thus, the left-hand ends of the springs 17 and 18 are anchored on a cross bar 19 extending

across the top of the typewriter space 50 and attached to the supports 10 and 12. The right-hand ends of springs 17 and 18 are engaged in apertures formed in an anchor member 20. This anchor member 20 has legs attached to links 9 (Fig. 2), as by the aid of the rivets 21. In the lowered position of Fig. 1, the force of the springs 17 and 18 on links 9 is directed to the left, and above, the pivots 22, 23 of the links 8 and 9. Accordingly, the force of the spring urges the links 8 and 9 in a direction to maintain the support 7 in the lowered position.

Now, when support 7 is moved forwardly, the anchor 20 moves downwardly and below the pivots 22 and 23. When this downward movement reaches a position where the direction of the force of the springs is below these pivots 22 and 23, the force of the springs is in a direction to move the links 8 and 9 in a clockwise direction. This clockwise direction is such as to raise the support 7 ultimately to the position of Fig. 3. In this position, the typewriter 24 is supported at a convenient height for operation. Similarly, when it is desired to lower the support 7, it may be urged downwardly and inwardly from the position of Fig. 3 until the springs 17 and 18 assume a position above the pivots 22 and 23.

The space between the opposed supporting bars 10 and 12 is slightly less than the width of shelf 7 and links 9. These links thus slightly diverge toward the shelf 7. When the shelf is raised to the position of Fig. 3, the shelf and links are thus wedged firmly in place, and all vibration is eliminated.

When the support 7 is in the raised position of Fig. 3, it is securely latched in this position until it is desired to lower the support. For this purpose, hooks 25 are disposed on opposite sides of the support 7. These hooks may be formed on the ends of a bent strap 26 that extends across the bottom of support 7. These hooks 25 are intended to engage a latch bar 27. This latch bar extends transversely across the top of the typewriter opening. It is guided, as by slots 28 located in the ends of the supports 10 and 12, and extends beyond these supports (Fig. 4). The slots 28 extend in a direction parallel to the supports 10 and 12, which direction is normal to the direction of movement of the support 7 when it is in the elevated position of Fig. 3. A pair of tension springs 29 is anchored at one end around the bar 27. At the other end, they are anchored on the spring anchor 19. These springs 28 urge the bar 27 into the slot 30 of each of the hooks 25.

The upper surface 31 of each of the hook members 25 is sloping so that, as the hook members are brought up to the position of Fig. 3, these sloping surfaces engage the bar 27 and urge the bar 27 outwardly of the groove 28. Then, as the sloping surface 31 moves further upwardly, the bar 28 moves inwardly to engage the slots 30. In the engaged position illustrated in Figs. 3 and 4, the bar 37 is hooked at each of its extremities. Since the support is suspended by hooks at each edge of the support, it is effectively prevented from tilting, as well as from moving downwardly, under the weight of the typewriter 24.

In order to release the bar 28 from the hooks 25, use is made of a lever 32 pivoted in a clevis 33 mounted on the support 7. This lever 32 has an arm provided with a sloping surface 34. This sloping surface, when the support 7 is in the raised position, underlies the bar 27, as shown

most clearly in Fig. 3. In order to release the bar 27, the lever 32 is moved in a counterclockwise direction, and the sloping surface 34 engages the bar 27 and moves it to the disengaged position of Fig. 5. In this position, the support 7 may be lowered, as the hooks 25 are no longer engaged by the bar 27.

In order to form a limit to the upward movement of the support 7, a cross member 35 is mounted in front of the clevis 33 on the support 7. This cross member is provided with a slot 36 to permit the passage of the lever 32. Its upper surface closely underlies the upper frame portion 37 of the opening to the typewriter space 50.

The inventor claims:

1. In a lift mechanism: a pair of parallel spaced frame elements having provisions for attachment to a cabinet or the like; a mechanism movably carried by said frame elements and comprising: a support, and a plurality of links pivoted at one end to said support, the other ends of some of the links being pivoted to one of said frame elements, the other ends of the other of said links being pivoted to the other of said frame elements, said links being of equal length between their pivotal mountings for providing a parallelogram suspension for said support; said support being swingable through substantially a quarter revolution from a first position to a second position; said frame elements each having at corresponding ends a slot extending in a direction transverse to the direction of movement of said support when said support reaches said second position; a bar extending between said frame elements and guided by said slots respectively for translation of said bar; a pair of spring members urging said bar to one position in said slots; and a hook member rigidly carried by said mechanism and having a cam surface engageable with said bar when said support is moved to said second position, and also having a latching recess engageable with said bar upon continued movement of said support, said recess extending substantially parallel to said slots when said support is in said second position.

2. In a lift mechanism: a pair of parallel spaced elongate frame members having provisions for attachment to a cabinet or the like; a mechanism movably carried by said frame members, and comprising: a support, a first pair of links each having one end respectively pivoted to one side of said support and each having another end respectively pivoted to one of said frame members, and another pair of links each having one end respectively pivoted to the opposite side of said support and each having another end respectively pivoted to the other of said frame members; said links all being of equal length between their pivotal connections for providing a parallelogram suspension for said support, said support being swingable from a first juxtaposed position with respect to said frame members to a second position in which said support is out of juxtaposed relationship with respect to said frame members, the length of each pair of links respectively between their pivotal connections being substantially parallel to said frame members when said support is in said second position; said frame members each having at corresponding ends a slot extending substantially parallel to the length of said frame members; a bar extending between said frame members and guided by said slots respectively for

translation of said bar; spring means urging said bar to one position in said slots; a hook member rigidly carried by said mechanism and having a cam surface engageable with said bar for moving said bar away from said one position when said support is moved to said second position, said hook member also having a latching recess engageable with said bar upon continued movement of said support, said recess extending substantially parallel to said slots when said support is in said second position; and manually operated means for moving said bar away from said one position and out of latching relationship with said bar.

3. In a lift mechanism: a pair of parallel spaced frame elements having provisions for attachment to a cabinet or the like; a mechanism movably carried by said frame elements and comprising: a support, and a plurality of links pivoted at one end to said support, the other end of some of the links being pivoted to one of said frame elements, the other ends of the other of said links being pivoted to the other of said frame elements, said links being of equal length between their pivotal mountings for providing a parallelogram suspension for said support; said support being swingable through substantially a quarter revolution from a first position to a second position; a pair of elements rigidly carried by said mechanism and each having a slot extending in a direction transverse to the direction of movement of said support when said support reaches said second position; said slots of said elements of saids mechanism having a substantial length movable into alignment with a substantial length of the slots of said frame members when said mechanism is in said second position; a bar guidingly carried at opposite ends in the slots of one of the pairs of elements; a spring exerting a force urging said bar to one position in said one pair of slots; said bar being movable to another position in said slots of said one pair of elements against the force of said spring; the slots of the other of said pairs of elements being open to provide a latching recess receiving said bar when said mechanism is in said second position; said bar, when said slots are aligned, clearing the open ends of the slots of said other pair of elements when said bar is moved from said one position to said other posi-

tion; and means providing cam surfaces on each of said other of said pairs of elements adjoining the slots thereof, and engageable with said bar upon movement of said support toward said second position to move said bar to said other position.

4. In a lift mechanism: a pair of parallel spaced elements forming a frame member, said elements having provisions for attachment to a cabinet or the like; a mechanism movably carried by said frame member and comprising: a support member, and a plurality of links each pivoted at one end to said support member, and at the other end to said frame member, said links being of equal length between their pivotal mountings for providing a parallelogram suspension for said support member; said support member being swingable through substantially a quarter revolution from a first position to a second position; a latch bar extending transversely of the mechanism; means carried by one of the members for guiding the bar for movement of translation transverse to the axes of the link pivots, and transverse to the direction of movement of said support member when said support is in said second position; a hook carried by the other member for engaging the latch bar; said hook having a cam surface engageable with said bar when the support member is moved to said second position, and also having a latching recess engageable with said bar upon continued movement of said support, said recess extending in the direction of movement of said bar; and means resiliently urging said bar into engaging position with respect to said recess.
